A. W. HALL.
STEAM PLOW.

No. 38,260.

Patented Apr. 21, 1863.

UNITED STATES PATENT OFFICE.

A. W. HALL, OF ST. LOUIS, MISSOURI, ASSIGNOR TO HIMSELF AND B. W. ROBINSON, OF SOUTH READING, MASSACHUSETTS.

IMPROVEMENT IN STEAM-PLOWS.

Specification forming part of Letters Patent No. 38,260, dated April 21, 1863.

To all whom it may concern:

Be it known that I, A. W. HALL, of the city and county of St. Louis, and State of Missouri, have invented a new and useful Improvement in Steam-Plows; and I do hereby declare that the following is a full and clear description thereof, reference being had to the accompanying drawings, and to the letters of reference marked thereon and made to form a part of this specification.

I am aware that many inventions and devices have been essayed with a view to the employment of steam as a motive power in plowing; but all such devices have failed to be adopted into general use for various reasons, among which may be mentioned, first, the enormous expense attending the construction of said devices; and, second, their great weight has rendered them impracticable for plowing in soft ground.

The object of my invention is the construction of a device which may be free from the above objections and by means of which the plowing of the various kinds of soil may be rapidly and cheaply performed, steam being employed as a motive power; and the nature of my invention relates to the arrangement or employment of an ordinary portable steam-engine, in combination with a series of adjustable traction pulleys or rollers, to be used in connection with a rope or chain stretched across the field and suitably anchored or fastened at each end, as hereinafter set forth, specified, and represented.

In reference to the accompanying drawings, Figure 1 is a side elevation of my invention, represented as being arranged upon an ordinary wagon-truck, a small portion of the framework being broken out in order to represent the mode of adjusting the pulleys or rollers. Fig. 2 is a front elevation, representing one set of the traction-pulleys.

A represents the frame or bed of the carriage, arranged upon four wheels, the axles of which, for practical use, will be so constructed and arranged with reference to the bed A that they may be operated in such manner as to enable the engineer or operator to guide and properly control the direction of the machine.

B represents the boiler, and C the engine.

d is a balance-wheel, which may be arranged upon the shaft of the driving-pulley.

E represents the pulley-frame, firmly secured to the bed A.

f f' represent a series of traction-pulleys provided at their ends with cog gear-wheels.

g represents intermediate gear-wheels, which are adapted to mesh and work into the cog-wheels of pulleys f. The pulleys f and wheels g are provided with suitable journals which are adapted to work in fixed bearings in uprights h of frame E. The journal-bearings of pulleys f' are adjustable vertically by means of the set-screws k in such manner as to secure the necessary friction or impingement upon the rope m. The said pulleys f f' may be formed with grooves i, Fig. 2, which is adapted to receive the rope m and prevent it from being too much flattened or otherwise injured by compression between the pulleys f f', while at the same time they are adapted to grasp and facilitate the necessary traction upon the said rope. The driving-pulley f'' of the series f f' will be provided with a shaft extending beyond the uprights h, and formed with a crank or cranks, by means of which said pulleys may receive motion from the engine.

n represents a gang of plows, which may be attached to the machine. It is intended to use plows with reversible shares, so that the said plows may be made to operate backward and forward upon the same side of the land to be plowed, and the attachment for the plows will be of such character that the plows may be made to operate at either end of the machine.

Having thus described the construction of my invention, I will briefly set forth the mode of operating the same.

The rope m, which may be of any desired length adapted to the size of the field to be plowed, will be stretched across and properly secured or anchored at each end of the field, being first passed through between the traction-pulleys f f'. The pulleys f' will be adjusted, as before described, so as to secure the proper traction or impingement upon the rope. The engine will then be started, by means of which the series of pulleys f f', through the medium of the driving-pulley f'' and wheels g, will be made to rotate upon the rope m, thereby drawing the machine and plows forward across the field. The rope will then be suitably adjusted, the plows reversed and attached to the other end of the machine, and the rota-

tion of the pulleys reversed. The machine will then return across the field, drawing the plows as before. This operation may be repeated, changing the position of and anchoring the rope at proper intervals, until the plowing may be accomplished.

I do not wish to confine myself to any peculiar kind or style of boiler or engine, or to the employment of a single engine, as it is obvious that various applications of power may be employed without departing from the spirit of my invention. Neither do I wish to confine myself to the use of a single rope or chain, as I am aware that a series of two or more ropes or chains may be employed for a like purpose; but I prefer the single rope, as herein described. Neither do I claim any peculiar mode of anchoring or securing the ends of the rope; neither do I confine myself to any particular number of the traction-pulleys, or to the kind of materials of or the style or form in which the same may be constructed, or to the relative position they may hold to the boiler, as it is

obvious the same may be varied without deviating from the gist of my invention; but,

Having described the construction and operation of my improvement, what I do claim as new, and desire to secure by Letters Patent, is—

The employment of a steam engine or its equivalent motive power, in combination with a series of two or more traction-pulleys, *ff'*, to be used in connection with a rope extended across and properly secured at each end of the field, all being constructed and arranged to operate in such manner that the said motive power may be made to draw itself and the gang of plows attached across the field, substantially as herein described and represented.

In testimony of which invention I have hereunto set my hand and seal this 3d day of January, 1863.

A. W. HALL. [L. S.]

In presence of—

H. E. CLIFTON,

A. E. SWIFT.
